KNIFE

Abb Bingham Bristo, Kansas City, Mo.

Application February 8, 1944, Serial No. 521,537

4 Claims. (Cl. 30—340)

This invention relates to cutlery and more particularly to a knife having a handle and a blade so formed that the handle and the blade may be taken apart and a new blade substituted in place of one in use in case the blade becomes broken or is worn to such an extent by repeated sharpenings that it is no longer serviceable.

Another object of the invention is to provide the blade with a shank consisting of front and rear sections having interengaging tongues to hold the two sections in firm engagement with each other, said sections carrying ribs for engagement in grooves formed in side grips disposed at opposite sides of the shank and together therewith forming a handle of such dimensions that it may be easily grasped in a person's hand when using the knife.

Another object of the invention is to provide hand grips so mounted that they are slidable longitudinally into and out of position at opposite sides of the shank, fasteners being provided for securing the hand grips in place and preventing them from accidentally slipping out of place against sides of the shank.

Another object of the invention is to provide a knife having a removable blade which may be easily removed when necessary but is not liable to work loose at other times.

The invention is illustrated in the accompanying drawing, wherein:

Figure 1 is a side elevation of the improved knife.

Figure 2 is a view showing one of the side grips removed, the blade being broken off near the handle.

Figure 3 is a sectional view taken longitudinally through the handle along line 3—3 of Figure 1 or Figure 2.

Figure 4 is a sectional view taken transversely through the handle along line 4—4 of Figure 1 or Figure 2.

Figure 5 is a perspective view of the shank of the blade.

The blade 1 of the improved knife may be of any length desired and the shank of the blade consists of companion front and rear sections 2 and 3, the front section being integral with the blade and the rear section being separate from the front section and detachably engaged therewith. The two shank sections are of duplicate formation and each has a plurality of tongues 4, 5, 6, 7 and 8. The tongues 6 and 8 are each straight throughout its length and tongues 4, 5 and 7 are hook shaped, tongue 4 being formed with a short bill 9 directed towards but termi-

nating in spaced relation to tongue 5. Referring to Figure 5 it will be seen that the tongues define pockets 10, 11, 12 and 13 to receive tongues 5, 6 and 7 of the companion shank section, the shank of the tongue 4 being set inwardly from the upper side edge of the shank section and defining a recess or pocket 14 to receive the tongue 8 of the companion shank section. This engagement of the tongues in the recesses or pockets 10 is shown in Figure 2, and referring to this figure it will be seen that when the two shank sections 2 and 3 are engaged with each other the tongues have interlocking engagement with each other and prevent the two shank sections from shifting longitudinally or transversely out of close fitting and aligned engagement. The two shank sections are of the same width and thickness and when they are in interlocked engagement with each other a shank is formed which is of even width and thickness throughout its length as shown in Figures 2, 3 and 4. The two shank sections must be firmly braced against any movement which might tend to separate them or allow transverse twisting movement of the blade 1 during use of the knife and in order to do so there have been provided ribs 15 formed from strip of metal or other stiff material. These strips which have undercut side edges, as shown in Figure 4, extend longitudinally of the shank midway the width thereof are secured against opposite side faces of the shank sections in opposed relation to each other by screws 16 passed through openings formed in one strip and screwed into threaded openings formed in the other strip. When the strips are in place and secured they firmly brace the shank sections against transverse play in a direction to dislodge the tongues from the pockets into which they fit. Since side edges of the strips are beveled, as shown in Figure 4, they form ribs having undercut side edges and when the side plates or hand grips 17 are slid longitudinally into place with the ribs engaged in the undercut recesses or grooves 18 formed in the hand grips, the hand grips will be prevented from shifting transversely away from the shank. Therefore the hand grips will be held close against the shank for the entire length thereof and when the bolts 19 are passed through the hand grips and screwed into the countersunk nuts 20 the two hand grips will be prevented from accidentally shifting longitudinally out of place. The hand grips may be formed of wood or other suitable material and have been shown ornamented by plates 21 which are countersunk in the outer faces of the hand grips and

secured by rivets 22. Under normal conditions the two shank sections will be firmly held together and the hand grips firmly held in place against opposite sides of the shank with the blade extending forwardly from the handle but if the blade should be broken or worn to such an extent by repeated sharpenings that it is too thin or too short it is merely necessary to remove the hand grips 15 and the strips 17 and the shank portion of a new blade applied to the rear shank portion, the strips and hand grips being then reassembled and secured by the screws and bolts.

Having thus described the invention, what is claimed is:

1. A device of the character described comprising a blade, a shank having front and rear sections each formed with spaced tongues defining pockets to snugly receive the tongues of the other section and interlock the tongues of the said sections to firmly hold the shank sections in engagement with each other, strips extending longitudinally of said shank in opposed relation to each other midway the width of the shank, said ribs having undercut side edges, removable fasteners for securing said strips against the shank sections, hand grips slid longitudinally into place against opposite sides of the shank and formed with longitudinally extending undercut grooves into which said strips fit, and removable fasteners passing through the hand grips and securing the hand grips against accidental displacement.

2. A device of the character described comprising a blade and a handle, said blade having a rear extension constituting a front shank sec-

tion, a rear shank section, said shank sections having portions overlapped in edge to edge engagement with each other and formed with tongue receiving recesses and tongues for engaging in said recesses and interlocking to hold the shank sections interlocked with each other, ribs extending longitudinally of said shank sections against opposite side faces thereof, hand grips at opposite sides of the shank formed with longitudinal seats, said strips being slid into said seats, and removable fasteners for securing said hand grips against accidental displacement.

3. A device of the character described comprising a blade, a shank for said blade having companion sections formed with recesses and with tongues engaged in the recesses, ribs at opposite sides of said shank extending longitudinally thereof, and hand grips detachably mounted at opposite sides of said shank and formed with recesses into which said tongues fit.

4. A device of the character described comprising a blade, a shank for said blade having companion sections formed with recesses and with tongues engaged in the recesses to hold in said sections in longitudinal alignment, ribs at opposite sides of said shank extending longitudinally thereof and undercut along their side edges, and hand grips detachably mounted at opposite sides of said shank and formed with undercut longitudinally extending recesses, said ribs being slid longitudinally into the recesses of said hand grips and holding the hand grips tight against opposite side faces of the shank.

ABB BINGHAM BRISTO.
